UNITED STATES PATENT OFFICE

ROBERT B. SCHINDLER, OF SPRING CITY, PENNSYLVANIA

DESIGN FOR A STOCKING

Application filed December 10, 1931. Serial No 42,028. Term of patent 3½ years.

To all whom it may concern:

Be it known that I, ROBERT B. SCHINDLER, a citizen of the United States, residing at Spring City, county of Chester and State of Pennsylvania, have invented a new, original, and ornamental Design for Stockings, of which the following is a specification, reference being had to the accompanying drawings, forming part thereof.

only a portion of the lace being illustrated it being understood that the remaining portion is the same as that now shown,

Figure 2 is a detailed enlarged view of a portion of the stocking leg fabric.

I claim:

The ornamental design for a stocking as shown and described.

ROBERT B. SCHINDLER.
